ROTISSERIE

Abraham S. Levin, Philadelphia, Pa.

Application October 7, 1954, Serial No. 32,580

Term of patent 14 years

(Cl. D81—10)

FIG. 1

FIG. 2

Fig. 1 is a front perspective view of a rotisserie embodying my design.

Fig. 2 is a top plan view of the same.

The right-hand side of the rotisserie is the same as the left-hand side thereof. The back of the rotisserie is plain.

I claim:

The ornamental design for a rotisserie, as shown and described.
